UNITED STATES PATENT OFFICE.

JOHN L. BARKER, OF RACINE, WISCONSIN, ASSIGNOR TO S. FREEMAN & SONS, OF SAME PLACE.

BRAKE-LEVER.

SPECIFICATION forming part of Letters Patent No. 270,174, dated January 2, 1883.

Application filed August 19, 1882. (No model.)

To all whom it may concern:

Be it known that I, JOHN L. BARKER, of Racine, in the county of Racine, and in the State of Wisconsin, have invented certain new and useful Improvements in Wagon-Brake Levers; and I do hereby declare that the following is a full, clear, and exact description thereof, reference being had to the accompanying drawings, and to the letters of reference marked thereon, making a part of this specification.

This invention relates to certain improvements in locks for the brakes of vehicles; and it has for its objects to provide for connecting the parts without the use of the ordinary rivets, and thereby obviate the expense of drilling and riveting the parts together, as more fully hereinafter specified. These objects I attain by the means illustrated in the accompanying drawings, in which—

Figure 1 represents a side elevation of my improved locking device; Fig. 2, a vertical sectional view of a portion thereof on the line xx of Fig. 1. Fig. 3 represents a vertical section taken at right angles to the line xx of Fig. 1, and Fig. 4 represents a detached perspective view of the link which connects the two levers.

The letter A indicates a board or plate carrying the working parts of my improved brake-lock; B a curved brace secured to the face of the board or plate, and C a segment secured to the said board and connecting with the brace before mentioned at D. The brace at its lower end is provided with a socket, E, in which is pivoted the lower end of a lever, F, as indicated in Fig. 1 of the drawings.

Upon the lever is mounted a sliding metallic frame, G, which also sets over and is adapted to move upon the segment C, the said segment being ratcheted or serrated at its lower edge, and the frame at one side being provided with a lip, H, adapted to engage the ratchets and hold the lever in any desired position, as indicated in dotted lines, Fig. 1. The said frame is provided with a recess, I, in which is adapted to slide a follower, K, which is held normally against the upper edge of the segment C by means of a spring, L, as shown in Fig. 2. The said follower bears

at one side against the lever F, and is of such size and shape as to be confined in the recess by means of said lever when the parts of the device are secured together, but which may be turned and removed when the frame is removed from the lever. 55

The frame at one side is provided with a recessed projection, M, having an inwardly-turned lip, N, which is adapted to engage a recess, O, near the end of the auxiliary lever P and hold it loosely in place, the lower end of said lever bearing against the edge of the lever F, which bearing serves as a fulcrum for the lever P. The lever P extends upward and terminates at the end of the lever F, the two being provided with handles R, by which they may be grasped. The two levers are connected near their upper ends by means of a link, S, which has cast with it the pivots T, adapted to enter suitable apertures in the handles. The said link is provided with shoulders U, which bear against the sides of the levers when the link is in place. 70

It will be seen that as thus constructed the follower and auxiliary lever will be held in place by the lever F, thus obviating the use of rivets or pivots and the necessity of drilling, thereby reducing the expense and producing a stronger device. The link, being cast in one piece, does not require to have the rivets subsequently attached, producing a stronger and less expensive link than heretofore. When in a normal position the parts set with respect to each other as indicated in Fig. 1, the frame engaging the ratchets on the segment, and holding the lever F in position. Upon grasping and bringing the upper ends of the levers together the frame is depressed, throwing the lip out of the ratchet, and permitting the lever F to be oscillated on its pivot or fulcrum. 90

Having thus described my invention, what I claim, and desire to secure by Letters Patent, is—

1. In combination with the lever F and segment C, the frame G, adapted to slide on said lever and segment, and engage and disengage the ratchet, the said frame being provided with a recessed projection, M, and inwardly-turned lip N, and the lever P, provided with a recess, O, into which the lip N projects, whereby the 100

said lever P is held without rivets, substantially as specified.

2. In combination with lever F, segment C, frame G, and lever P, the follower and spring located in a recess in the frame, whereby the parts are held in normal position, substantially as specified.

3. In combination with the levers F and P, the link S, provided with shoulders U and

pivots T, all cast in one piece, substantially as to and for the purpose specified.

In testimony whereof I affix my signature, in presence of two witnesses, this 27th day of June, 1882.

JOHN L. BARKER.
